UNITED STATES PATENT OFFICE.

JOHN R. GREEN, OF KANSAS CITY, MISSOURI.

HYDROCARBON-BURNER.

1,021,186.

Specification of Letters Patent. Patented Mar. 26, 1912.

Application filed January 31, 1911. Serial No. 605,761.

To all whom it may concern:

Be it known that I, JOHN R. GREEN, a citizen of the United States, residing at Kansas City, in the county of Jackson and State of Missouri, have invented certain new and useful Improvements in Hydro-carbon-Burners, of which the following is a specification.

My invention relates to hydro-carbon burners.

The object of my invention is to produce a hydro-carbon burner which is simple in construction, efficient in operation, and which will economically produce a very hot flame.

The novel features of my invention are hereinafter fully described and claimed.

In the accompanying drawing, which illustrates my invention in its preferred form, Figure 1 is a side elevation of my improved burner. Fig. 2 is a top view of the same. Fig. 3 is a vertical section on the dotted line *a—b* of Fig. 1.

Similar reference characters denote similar parts.

1 denotes a body having a steam chamber 2, one end of which is normally closed by a screw threaded cap 3 which engages the screw threaded end of the body. A conductor 4 having a cut off valve 5 is connected at one end with a suitable water supply, not shown, the other end being extended through and secured, preferably by screw threaded connection with the cap 3. The said conductor 4 serves as a water inlet for the steam chamber 2. The opposite end of the body 1 is provided with an upwardly extending goose neck portion 6, through which extends a downwardly inclined oil duct 7, having connected to its upper end an oil conductor 8, preferably of U form, and having its other end connected to an oil tank 9, disposed, preferably so that the oil will flow by gravity through the conductor 8 to the duct 7. By having the conductor of U form, any small amount of sediment passing from the tank 9 will collect at the bottom of the U instead of passing into and possibly clogging the duct 7.

In the conductor 8 is located a shut off valve 10.

The goose neck end of the body 1 is preferably provided with an inclined plane deflecting surface 11 disposed so that a jet discharged from the outlet end of the oil

duct 7 will strike and be deflected and diffused by said plane surface 11. In the goose neck portion 6 is provided a steam passage 12 which, at one end communicates with the chamber 2 adjacent to but separated from the top of said chamber. The other end of the passage 12 discharges, as is shown in Fig. 3, into the oil duct 7 toward the outlet thereof. The steam pressure is thus added to the gravity pressure of the oil for forming the jet which is impinged against the deflecting surface 11.

It will be noted that the discharge end of the duct 7 is downwardly inclined and substantially perpendicular to the plane surface 11. By having the said duct downwardly inclined at its discharge end, all of the oil will run out of said end when the use of the burner ceases, thus eliminating the liability of the end of the duct being clogged by oil remaining therein. By having the discharge end of said duct substantially perpendicular to the plane surface 11, a greater heating effect is produced than would be effected if the duct were disposed so as to be oblique to said plane surface. In the latter case a current of air would be produced which would tend to cool the surface.

As will be seen by referring to Fig. 3, the duct 7 and steam passage 12 are so connected with each other, that the oil passing through the duct 7 will not run down into the steam passage, but will run out the outlet end of the duct 7, when there is no steam pressure, as well as when there is a steam pressure. Supported by one or more devices, such as screws, 13, secured to the under side of the body 1 is a drip pan 14, so disposed as to catch, in the ordinary manner oil dripping from the duct 7.

In operating my invention, the valve 10 is first opened, thus permitting oil to pass from the tank 9 through the conductor 8 to and through the duct 7. From the duct 7 it will run into the drip pan 14. When a sufficient quantity has been collected in the drip pan, the valve 10 is closed and the oil in the pan ignited, thereby heating the body 1 sufficiently to change water entering the chamber 2 into steam. The valve 5 is then opened, thus permitting water to flow through the conductor 4 into chamber 2 where the water is converted into steam, which passes through the passage 12 and

mingles with oil, which is now permitted to pass into the duct 7 by opening the valve 10. The jet composed of steam and oil is then ignited. The heat of the burning jet retains the body 1 sufficiently heated to convert the water entering the chamber 2 into steam, thereby continuing the process.

By having the inlet end of the passage 12 located adjacent to but slightly lower than the top of the chamber 1, the steam carried from the chamber is neither too dry nor too wet, but contains the proper amount of moisture to effect the greatest heat when burned with the oil. If the inlet end of the passage 12 is located at the extreme top of the chamber the steam is too dry for the best effects, and if located too low the large amount of moisture carried with the steam lowers the heating power of the flame. Thus by locating the inlet end of the passage 12 just below the top of the chamber I obtain the largest heating power in the flame.

Various modifications of my invention, within the scope of the appended claim, may

be made without departing from the spirit of my invention.

Having thus described my invention, what I claim and desire to secure by Letters Patent, is:—

In a hydro-carbon burner, a body having a goose neck portion and a portion with a plane deflecting surface, the body having extending through the goose neck portion an oil duct the discharge end of which is 35 downwardly inclined and substantially perpendicular to and is adapted to discharge a jet against said plane surface, the body having in the portion having the plane surface and in the goose neck portion a steam 40 passage, the discharge end of which discharges into the oil duct toward the discharge end thereof.

In testimony whereof I have signed this specification in presence of two subscribing 45 witnesses.

JOHN R. GREEN.
